H. E. DECKEBACH

PROCESS OF INCREASING EFFICIENCY OF DISTILLATION

Filed June 23, 1920

Patented Dec. 23, 1924.

1,520,121

UNITED STATES PATENT OFFICE.

HENRY E. DECKEBACH, OF CINCINNATI, OHIO.

PROCESS OF INCREASING EFFICIENCY OF DISTILLATION.

Application filed June 23, 1920. Serial No. 391,234.

To all whom it may concern:

Be it known that I, HENRY E. DECKEBACH, a citizen of the United States of America, and resident of Cincinnati, in the 5 county of Hamilton and State of Ohio, have invented a new and useful Improvement in Processes of Increasing Efficiency of Distillation, of which the following is a specification.

10 An object of my discovery and invention is to increase the quality and quantity of any distillate or oil, produced from any crude oil or crude product that can be distilled.

15 Another object is to accomplish the fore-mentioned object by increasing the generating and circulating power of such crude material during distillation.

Another object is to provide a process that 20 does not require the high temperature necessary in the present general practice.

This and other objects are attained by the steps hereinafter described, and by means of the apparatus disclosed in the accompany- 25 ing drawing in which:—

Fig. 1 is a sectional elevation on line 1—1 of Fig. 2.

Fig. 2 is a sectional view on line 2—2 of Fig. 1.

30 Fig. 3 is an enlarged sectional view on line 3—3 of Fig. 2.

I will explain the parts and operation of the apparatus before explaining the process.

The boiler or tank A has near its bottom, 35 the steam feed pipes a and a' , terminating at opposite ends of the tank. Mounted upon the ends of the feed pipes are the siphons a^2 and a^3 , each having a hollow and downwardly projecting draw tube a^4 , terminating 40 immediately adjacent to the lowest part of the interior of the tank. A projector tube a^5 extends upward from the siphons and terminates in a bent top a^6 adapted to extend above the surface of the product to be distilled and to emit the substance passing thru the feed pipes, the siphons, the projector tubes and the vaporizing nozzles a^7 , above the surface of the material to be distilled. The projector tubes are supported by the 45 arms a^8 extending from the tank A. From this it is readily apparent that only the hottest material within the tank will pass thru the siphon projector tubes, when steam or hot air is sent thru the feed pipes a and a' , thereby drawing the material to be distilled thru the draw tubes and siphons. The

material to be distilled is projected from the projector tubes, vaporized above the material and passes off to the condensing pipe or coil C.

60 The process with which I use the foregoing apparatus is as follows:

I do not change the regular method of distillation as used in producing gasoline, naphtha, kerosene, gas oil, fuel oil, etc., but I 65 add thereto and increase and improve their quantity and quality by taking three per cent (3%) of the finished or partly finished distillate and injecting or introducing it 70 into the crude oil during or before distillation, thereby increasing the energy with which the distillation proceeds. This alone produces ten per cent (10%) more finished distillate than can be obtained by the regular method. The distillate may be added to 75 the crude oil thru valve D and feed pipe a . This distillation is carried on first at a temperature of 210 degrees F. to 275 degrees F. until no more distillate comes off between those temperatures, then the temperature is 80 raised and maintained from 275 degrees F. to 315 degrees F. and when no more distillate comes off, the temperature is maintained between 315 degrees F. and 340 degrees F.

85 In the fourth stage the temperature is raised to and maintained between 340 degrees F. and 480 degrees F. Thereafter no more distillate comes off.

In addition to the foregoing I inject 90 heated air or superheated steam into the tank, by means of the feed pipes, siphons and projector tubes, thereby causing extra circulation in the heated oil because of the heat radiating from the feed pipes, and because of the hottest oil on the bottom of the tank being drawn thru the siphons and being vaporized as it is thrown from the vaporizing nozzles, thereby creating pressure above the surface of the material to be 95 distilled, such pressure forcing the vapor 100 out of the tank, and into the condenser C.

The advantage of the described process over the general practice is that in the general practice, hot air or gas is introduced 105 in the bottom of the tank by means of perforated pipes, that release the gas in the material. If the pressure of this gas is too great, it lifts the material and causes it to boil over into the condenser. The addition 110 of the finished distillate to the material causes a quicker release and vaporization of

the product. Another feature of importance is that lower temperatures can be employed in the process disclosed by me than is usually employed in the general practice.

5 The lower the temperature at which distillation is carried on, the less carbon there will be in the finished product, consequently the quality of the finished product is raised.

What I claim is:

10 1. The process of providing a quantity of crude oil, providing a mixture of steam and fluid petroleum distillate, withdrawing part of the crude oil admixing crude oil withdrawn from the mass of crude oil with the 15 admixture of the steam and fluid distillate and discharging same above the body of the crude oil.

20 2. The process of heating a quantity of crude oil, providing a mixture of steam and fluid petroleum distillate withdrawing part

of the crude oil and admixing the steam and fluid distillate with the crude oil and discharging the admixture above the body of the crude oil.

3. The process of heating a quantity of 25 crude oil providing a mixture of steam and fluid petroleum distillate, directing a confined flow of the mixed steam and fluid distillate upwardly through the crude oil, admixing the crude oil with the mixed fluid 30 distillate and steam within the body of the crude oil and discharging the admixture of steam, fluid distillate and crude oil above the body of the crude oil and thereby creating a circulation in the crude oil. 35

In witness whereof, I have hereunto subscribed my name this 21st day of June, 1920.

HENRY E. DECKEBACH.
